[57]CLAIM

The ornamental design for a combined applicator and dispenser for oil and lotion, as shown and described.

DESCRIPTION

FIG. 1 is an exploded isometric view of a combined applicator and dispenser for oil or lotion showing my new design with the handle extended;

FIG. 2 is a top view shown with the cap in place;

FIG. 3 is a front view thereof, with the handle retracted;

FIG. 4 is a right side view thereof;

FIG. 5 is a back view thereof;

FIG. 6 is a left side view thereof;

FIG. 7 is a bottom view thereof;

FIG. 8 is an exploded isometric view of a second modified embodiment showing the handle extended;

FIG. 9 is a top view of the second embodiment with the cap in place;

FIG. 10 is a front view thereof, with the handle retracted;

FIG. 11 is a right side view thereof;

FIG. 12 is a back view thereof;

FIG. 13 is a left side view thereof;

FIG. 14 is a bottom view thereof;

FIG. 15 is an exploded isometric view of a third modified embodiment showing the handle extended;

FIG. 16 is a left side view of the third embodiment with the cap in place, the undisclosed sides being identical to that of the first disclosed embodiment except for the omission of the rectangular indicia area;

FIG. 17 is an exploded isometric view of a fourth modified embodiment, the undisclosed sides being identical to that of the second embodiment except for the appearance of the surface of the applicator head;

FIG. 18 is an exploded isometric view of a fifth modified embodiment showing the handle extended;

FIG. 19 is a top view of the fifth embodiment with the cap in place;

FIG. 20 is a front view thereof, with the handle retracted;

FIG. 21 is a right side view thereof;

FIG. 22 is a back view thereof;

FIG. 23 is a left side view thereof; and,

FIG. 24 is a bottom view thereof.

The cord element is shown partially broken away in the various views to indicate indeterminate length.
